UNITED STATES PATENT OFFICE.

LUCIUS ROBERTSON, OF CINCINNATI, OHIO.

ARTIFICIAL-TOOTH PLATE.

1,226,382.

Specification of Letters Patent.

Patented May 15, 1917.

Application filed March 3, 1917. Serial No. 152,401.

To all whom it may concern:

Be it known that I, LUCIUS ROBERTSON, a citizen of the United States, residing at the city of Cincinnati, in the county of Hamilton and State of Ohio, have invented certain new and useful Improvements in Artificial-Tooth Plates, of which the following is a specification.

My invention relates more particularly to 10 plates and teeth for the lower jaw. Inasmuch as plates for the lower set of teeth are held in the mouth almost wholly by weight and gravity, it has been very difficult to produce plates which will operate properly in 15 the mouth and not become dislodged.

The object of my invention is to produce a unique and highly serviceable combination of plate and teeth which will fit the alveolar ridge in such a manner that they will hold 20 their normal position when in place, and render the required service expected in plates of this character.

In carrying out my invention I place the teeth inside the alveolar ridge instead of on 25 the apex so that the teeth on the lingual side of the alveolar ridge will be flush, or approximately so with the inner side of the plate, thus giving the tongue sufficient and ample 30 room for play; and I finish the teeth on the outside in connection with the plate, extending 35 the rubber of the plate out materially on the labial side of the alveolar ridge so that all the membranes on the inside of the mouth and cheeks will coöperate to hold the plate in normal position.

The various features and advantages of my invention will readily become apparent from the following specification.

In the accompanying drawing forming 40 part of this specification,

Figure 1, is an isometric view of a plate and teeth for the lower jaw made after my invention, partly broken away to show construction,

Fig. 2, is a side view of an upper and lower plate and teeth, to illustrate how the lower set appears relatively to the upper set when made after my invention, and

Fig. 3, is a cross section on line 3—3 of 50 Fig. 1.

The alveolar ridge is marked 1, and onto this ridge is fitted the plate carrying the artificial teeth. This plate is marked 2 and is

preferably made of rubber, the teeth 3 being inserted therein and connected therewith. 55 This plate and the teeth may be made of any suitable material.

The plate or part which fits over the alveolar ridge 1 is, by me, shaped as shown in Fig. 3.

On the lingual side of the alveolar ridge 1, I place the teeth 3; they are set in to be flush with the lingual side of the ridge. The teeth are made of porcelain and have at their lower extremity a dovetail 4 into which the rubber of the plate enters to make a proper holding connection between the teeth and the plate. Small screws or pins 5 are also placed in the teeth, around which the rubber of the plate forms and is held in place. 70 These pins or screws 5 are placed in the rear or lingual side of the alveolar ridge 1, but I place them in front on the labial side. This enables me to finish the teeth and plate in a needed manner on the alveolar ridge. I 75 build up this side materially so that the plate may be kept in the mouth more perfectly.

What I claim as new and my invention and desire to secure by Letters Patent, is:

1. A dental plate for the lower jaw comprising a channel-shaped curved portion to cover the alveolar ridge and a set of false teeth fastened therein, said teeth set inside the alveolar ridge so as to be flush on the 85 lingual side, and the labial side of the teeth being flush with the inner side of the alveolar ridge, said curved portion extending out materially on the labial side of the alveolar.

2. In artificial teeth, a plate made of a 90 suitable material and capable of passing over the alveolar ridge, the teeth set back of the alveolar ridge on the lingual side thereof, and the labial side of the teeth being flush with the inner side of the alveolar 95 ridge, said plate being materially enlarged on the labial side of the alveolar ridge so that the membranes of the mouth and cheeks will contact with the same and tend to hold it in normal position.

Witness my hand at Cincinnati, Ohio, 100 Aug. 12th 1916.

LUCIUS ROBERTSON.
